CENTRIFUGAL PUMP

Rudolph D. Schott, Pomona, Calif., assignor to
 Pomona Pump Co., Pomona, Calif., a corpora-
 tion of Delaware

Application December 30, 1938, Serial No. 248,596

2 Claims. (Cl. 103—102)

This invention relates to centrifugal pumps and is especially applicable to turbine pumps used in connection with deep wells.

In the normal use of centrifugal pumps, and particularly in the case of turbine pumps used in deep wells, there is a tendency for a vertical or axial vibration to develop due to the natural frequency of the system comprising the suspended shaft which naturally carries a hydraulic load at its lower extremity. In a deep well turbine pump, the pressure head is produced by centrifugal force imparted to the fluid by one or more impellers, depending upon the depth of the well and the number of stages required for maintaining the desired flow. The upper end or surface of the impeller is exposed to the pumped fluid and, as a consequence, is under pressure from above and subject to all variations in pressure and flow of the fluid. Also, the impeller being suspended from the ground surface on a rotary shaft, it is subject to unequal loading. Under these conditions, there is a tendency to set up a vertical motion of the impeller which is reflected in the shaft which is under tension. This vertical motion induced by the inequality of pressure on the impeller synchronizes with the natural frequency of vibration of the suspended rotary shaft on which the impeller is fixed and causes a vertical vibratory motion of the entire system which increases in amplitude to a maximum coincidental with the natural frequency of the system. This vertical vibration thus assumes such proportions as to result in a pounding with sufficient force to seriously deform and, in some instances, to actually wreck the assembly.

The primary object of the present invention, therefore, is to provide a centrifugal pump with means for preventing or precluding the setting up of this vibratory motion.

A further object is to provide an incompressible mass or body between the impeller and the bowl which, at least, partially encloses or houses the impeller, the bowl being fixed to the well casing or pump eduction pipe whereby the incompressible body will prevent movement of the impeller axially toward the bowl.

More specifically, the invention contemplates a centrifugal pump wherein the bowl which, at least, partially houses the impeller is recessed to form a comparatively large cavity to which the pumped liquid has access from a point above the impeller. This cavity is formed in the lower surface of the bowl and is closed by the impeller itself, the upper surface of the impeller being rather fully exposed to the cavity, so that liquid

trapped in the cavity will form an incompressible body whereby it is impossible for the impeller to move toward its bowl. Preferably, this liquid is trapped in the cavity by sealing engagement between the impeller and bowl cavity, so that the liquid cannot escape, the inlet passage being the only opening leading to the cavity.

With these and other objects in view, the invention consists in certain details of construction and combinations and arrangements of parts, all as will hereinafter be more fully described, and the novel features thereof particularly pointed out in the appended claims.

In the accompanying drawing—

15 Figure 1 is a longitudinal sectional view of a turbine pump embodying the present improvements, said pump, in the present instance, being illustrated as comprising only a pair of impellers housed in bowls suspended from the well casing; and

20 Fig. 2 is a transverse sectional view on the line 2—2 of Fig. 1.

25 In accordance with usual practice, bowls 10, 11, of the pump adapted for illustrating the invention, are secured together by cap screws and, at the upper end of the bowl 10, this assembly is secured to the lower extremity of the well casing or eduction pipe 12. Usually, an inlet section 13 is secured by screws to the lower end of the lower bowl, said inlet section having a bearing 14 in the interior thereof for the lower end portion of the driving shaft 15 of the pump.

30 As will be understood, each bowl at least partially houses or encloses an impeller, the two impellers in the present instance being indicated at 16, 17. The impellers are, of course, rigidly mounted on the driving shaft which is adapted to be rotated by suitable power-actuated mechanism at the surface of the ground. Each of the 35 bowls is also formed in its interior with a hub portion 14a encircling the driving shaft 15 but spaced axially of the shaft from the hub of its impeller.

35 In carrying out the present invention, one or 40 more of the bowls and the impeller or impellers enclosed therein, is provided with an incompressible mass interposed between the bowl and impeller, whereby it is impossible for the impeller to move axially toward the bowl. However, it is not necessary or essential that each and every one of the bowls and its associated impeller be so formed. In the present instance, the upper bowl 10 and its impeller 16 are each of what might be termed normal construction or formation, but in the case of the bowl 11 and its im-

steller 17, it will be observed that a comparatively large cavity 18 is formed in the lower surface of the hub portion of the bowl. In the absence of the impeller, this cavity would be open at the lower surface of the bowl hub but, with the impeller assembled in the bowl, the impeller substantially seals the lower end of the cavity. Preferably, the impeller is formed with an annular recess 19 in its upper surface which, in effect, constitutes a continuation of the cavity 18, this annular recess being defined at its outer edge by an annular flange 20 which slidably telescopes, so to speak, the annular surface of the cavity in the bowl hub. If desired, a liner ring 21, preferably of rustless steel, may be secured in the lower edge portion of cavity 18 for engagement with the flange 20 on the impeller.

Bearing sleeves 22 for the shaft 15 are usually provided in the hub portion 14^a of each bowl but, with the present construction, there is a limited clearance between the shaft and its sleeves and the bowl hub portion or at least sufficient clearance to permit fluid to enter the cavity 18. It might be said that the under surface of the impeller is the suction side thereof, while the area above the impeller is the pressure side, as the water above the impeller will, of course, be under pressure. Due to the fact that the water is under pressure, the entry of water through the more or less minute openings around the shaft to the cavity 18 is augmented. As a result, this cavity between the impeller and the hub portion of the bowl becomes filled with water. This cavity is formed essentially in the bowl, although, in the present structure, the recess 19 in the impeller might be said to constitute an extension thereof. The flange 20 on the impeller forms substantially a seal with the liner ring 21 and thus the water entering the cavity 18 is trapped therein. Thus, with this body of water confined in the space between the impeller and bowl, it constitutes a substantially incompressible mass or body and, as a result, the vibratory motion that would ordinarily be set up is absolutely precluded by reasons of the fact that the impeller cannot move axially toward the hub portion of the bowl. It is not a case of overcoming a vibratory motion once set up. With the present arrangement, the vibratory motion never comes into existence. It is correct to say, with the present construction, the vibratory motion that would otherwise be present is absolutely damped out.

It will be appreciated that the number of associated bowls and impellers may be varied in accordance with the necessities in connection with any particular well and, likewise, that any number of the bowls and their impellers may be formed to provide this incompressible mass between them. The type of construction illustrated is applicable to all types of impellers including fully enclosed and semi-enclosed impellers for all deep well pumping of liquids. In a broad sense, it is contemplated that a material, other than the liquid pumped by the pump, may be used

for the incompressible body between the bowl and impeller, but it is preferred to use the liquid pumped by the pump because there is less likelihood of contamination of the liquid being pumped. The liner ring 21 against which the flange 20 of the impeller has a close working fit permits ready replacement in the case of undue wear, although the liquid pumped will function as a lubricant to minimize wear at this point.

With the exception of the provision of the cavity 18 in the hub portion of the bowl, the bowl may otherwise be of ordinary construction. It might be added that the hub portion of the bowl is supported by any number of webs 23 connecting said hub portion with the outer shell of the bowl.

While a deep well turbine pump has been adapted for purposes of illustrating the present invention, it will be appreciated that the invention is applicable to centrifugal pumps generally, of either the vertical or horizontal type and the appended claims are not to be limited to any specific type of centrifugal pump, except where expressly specified.

What I claim is:

1. A centrifugal pump for wells, having a rotary shaft adapted to be suspended in the well, an impeller fast on said shaft, and a bowl for housing said impeller and having a bearing through which said shaft extends, characterized by said bowl and impeller having a chamber formed between them by an imperforate annular flange on one of said members telescopically engaging an imperforate annular surface on the other member, said chamber being substantially sealed by said telescoping imperforate surfaces, and the bearing clearance between said bowl and shaft affording communication between said chamber and the flow-passage of the pump at a point on the pressure side of the impeller, to permit well fluid to pass into and out of said chamber, whereby fluid trapped in the said chamber will form a substantially incompressible mass between the impeller and bowl and resist the tendency of the impeller to move axially toward the bowl under self-induced vibration.

2. A centrifugal pump for wells having a rotary shaft adapted to be suspended in the well, an impeller fixed on said shaft, and a bowl for housing said impeller, characterized by said bowl having a cavity formed therein with the pressure side of the impeller exposed to said cavity, a passage through which well fluid can flow into and out of said cavity, said impeller and bowl having imperforate annular surfaces telescopically engaging one another substantially sealing said cavity at all times, except for said passage, and said passage being restricted whereby fluid trapped in said cavity will form a substantially incompressible mass between the impeller and bowl and resist tendency of the impeller to move axially toward the bowl under self-induced vibration.
